UNITED STATES PATENT OFFICE.

FRIEDRICH ALBIN SCHANZ, OF DRESDEN, GERMANY.

SIGHT FOR GUNS.

No. 861,396.

Specification of Letters Patent.

Patented July 30, 1907.

Application filed September 7, 1905. Serial No. 277,386.

To all whom it may concern:

Be it known that I, FRIEDRICH ALBIN SCHANZ, a subject of the King of Saxony, residing at Dresden-A, Germany, have invented certain new and useful Im- 5 provements in or Relating to Sights for Guns, of which the following is a specification.

The use of day-light strengthened by reflection, or of artificial light, in sighting devices for guns, more particularly in mirror-sighting devices, is in itself well known. Hitherto, however, only the sighting mark or rear sight itself was lighted, so that the sighting or front mirror and the notches used for sighting, in addition to the sighting mirror and the lighted sighting mark, remained dark, so that on the whole very little 10 was gained. It is not much use seeing a bright reflection of the sighting mark when the mirror—apart from the insufficient visibility of the notches—cannot be seen, and consequently it is impossible to determine in a reliable manner the proper position of the mark 15 relatively to the mirror.

According to this invention, however, aiming in failing or insufficient day light is substantially facilitated by lighting, not only the sighting mark, but also the sight mirror, by means of strengthened natural light 20 or by artificial light so that the counter-part of the sighting mark can be clearly seen in the lighted mirror, and consequently the position of the sighting mark relatively to the sight mirror can always be exactly determined. To that end the whole surface of the 25 bright sighting shield with the dark sighting mark, is lighted, and, if made of suitable material, such as dull glass, rendered transparent. The bright image of the sighting shield simultaneously lights the mirror surface, the dark sighting mark becoming visible in the 30 mirror, and enables the counter-mark arranged on it, or preferably, a recess, as described in my prior patent, to be clearly seen.

A construction of the new sighting device by means of which both day light and artificial light can be used, 35 as applied to a rifle, is illustrated, by way of example, in the accompanying drawing.

Figures 1 and 2 show the stock and the breech end of the gun, respectively, in side elevation, partly in section, and in plan. Fig. 3 is a section on the broken line 3-3 of Fig. 2. Fig. 4 shows a front elevation of the prism and prism-support, Fig. 5 being a plan of the same. Fig. 6 shows the sight mirror from the back, Fig. 7 the sighting shield from the front, Fig. 8 the sight mirror showing the reflection of the sighting mark, and Fig. 9 is a diagrammatic general view.

In the well known manner the front sight is replaced by a mirror *a* with a notch *b* adapted to be laid on the

target *Z* (Fig. 8). The back sight is replaced by a shield *c* of ground or translucent glass, with a T-shaped dark mark *d*. The aim is effected, according to Fig. 8, by bringing the image *d'* of the sighting mark appearing in the mirror *a*, so that its top coincides with the recess *b* or the target *Z*.

Behind the sighting shield is a holder or support *e* with a dovetail recess into which can be introduced a slide *f* (Fig. 5). The latter carries a prism *g* pivoted at *h*. If, unlike Fig. 5, the reflecting surface *g'* were arranged obliquely upwards and forward, the day-light from above would be reflected forwards and on the back of the sighting shield *c*, so that the latter would become transparent. In that position the sighting shield and therefore also the sighting mirror would be lighted by increased day-light. If, on the contrary, the prism or reflecting surface is, as in Fig. 5, arranged sideways, towards an incandescent lamp *i* (Fig. 2) the light of the incandescent lamp will be projected on the sighting shield *c*. By turning the prism *g* to the extent of 90° about the slide *f*, it is possible therefore to set the apparatus for day light or for electric light. It is obvious that the prism could be replaced by an obliquely placed mirror.

Current for the incandescent lamp can be supplied by an interchangeable dry battery *k* arranged in the stock of the gun and connected to the lamp by means of wires *l* and *m* (Fig. 2), connected to spring contacts *n* and *o*. When a slide *p* provided on the rifle, is moved forward, a cam projection *q* thereon moves a pin *r* inwards to bring the springs in contact and close the circuit.

What I claim as my invention and desire to secure by Letters Patent is:—

1. A sight for fire arms comprising a translucent rear shield having a sighting mark in its forward face, a rearwardly facing front mirror provided with a sight, said mirror and plate being so located that the reflection of the mark, the sight on the mirror and the target will be brought into a single line when the fire arm is properly sighted, and a light reflector adjacent to the rear shield, whereby both said rear shield and front mirror are illuminated substantially as described. 95

2. A sight for fire arms comprising a translucent rear shield having a sighting mark on its front face, a rearwardly facing front mirror having a central sighting notch, said mirror and plate being so positioned that the reflection of the mark, the notch and the target will be in line when the fire arm is properly sighted and a light reflector for lighting both the rear shield and the front mirror, whereby the notch and sighting mark may be readily aligned substantially as described. 100

3. A gun sight comprising a mirror foresight a translucent shield carrying a distinct mark constituting the backsight and a light reflector adjacent to the backsight whereby said back sight will be lighted and through it a

beam of light will be thrown upon the front mirror substantially as set forth.

4. A gun sight comprising a mirror foresight a translucent shield carrying a distinct mark constituting the backsight and an adjustable light reflecting prism adjacent to the backsight substantially as set forth.

5. A gun sight comprising a mirror foresight, a translucent shield carrying a distinct mark, constituting the backsight and an adjustable light reflecting prism adjacent to the backsight substantially as set forth.

cent to the backsight, in combination with an incandescent lamp adjacent to the reflector substantially as set forth.

In testimony whereof I have signed my name to this specification in the presence of two subscribing witnesses.

FRIEDRICH ALBIN SCHANZ.
